UNITED STATES PATENT OFFICE.

THOMAS PERRY BROCKETT, OF GOLDSBORO, NORTH CAROLINA.

JACK.

Application filed October 14, 1924. Serial No. 743,606.

To all whom it may concern:

Be it known that I, THOMAS P. BROCKETT, a citizen of the United States, and resident of Goldsboro, in the county of Wayne and 5 State of North Carolina, have invented certain new and useful Improvements in Jacks, of which the following is a specification.

My invention relates to improvements in jacks and it consists in the combinations, 10 constructions and arrangements herein described and claimed.

An object of the invention is to provide a jack of simplified construction which will afford facilities for making use of a relatively small force for causing relative movement of two separate movable members in a straight line against a relatively great resistance, if required, and for holding such members against accidental movement from 20 adjusted positions either toward each other or away from each other as desired and as determined by the position of the jack in respect to said members.

Other objects and advantages of the invention will be apparent from the following description, considered in conjunction with the accompanying drawings, in which—

Figure 1 is a side elevation of the improved jack in applied position with respect to two movable members on oppositely extending supports from a water meter, the latter being shown diagrammatically, and

Figure 2 is a section substantially along the line 2—2 of Figure 1, the water meter exhibited in Figure 1 being omitted.

A jack embodying the invention comprises a pair of substantially L-shaped or right angular spacing or pressure exerting members, each of which comprises a straight 40 attaching end portion 1, a straight contact end portion 2 and an intermediate bend portion 3 by means of which the attaching portion 1 and the contact portion 2 are merged one into the other. The attaching end portion 1 is circular in cross sectional contour and is provided with external screw threads as indicated at 4. A coupling or sleeve nut 5 has right and left hand internal screw threads extending along the bore thereof 50 from its opposite ends toward the transverse median line of the coupling nut for engaging with the threaded end portions 4 of the respective pressure exerting members when said members are arranged with the 55 end portions 4 thereof extending toward

each other in a straight line as clearly shown in Figure 1.

The contact portions 2 therefore will be held in parallel relation to each other and the distance between such contact portions 60 can be varied at will within a considerable range by turning the coupling nut 5 on the threaded end portions 4 so that such threaded end portions will be moved axially toward or away from each other, as desired. 65

Each of the contact portions 2 is provided with a pair of forks 6 at its extremity, the respective forks being offset laterally from opposite sides of the main portion of the contact member 2 and being adapted to 70 straddle and have sliding movement along a supporting member which is disposed parallel to the coupling nut 5 when the latter has been manipulated in the manner described. 75

A set screw 7 is in threaded engagement with a transverse opening 8 in one of the branches 6 of each of the contact portions 2 and may be tightened against the member which is straddled by the branch 6 to releasably hold the contact portion 2 against movement from adjusted position along the supporting member. 80

From the foregoing description of the various parts of the device, the operation thereof may be readily understood. The device is shown in Figure 1 in position to hold two members 9 and 10 which are slideable on aligned tubular members 11 and 12 respectively extending from opposite sides 85 of the base portion of a water meter 13 against moving from the full line positions along the supporting members 11 and 12 toward each other. It will be understood that the members 9 and 10 may have been moved from the dotted line positions of Figure 1 to the full line positions on the supporting members 11 and 12 against a relatively great resistance, if required, as a result of manipulation of the coupling nut 5 to cause 90 axial movement of the attaching portions 4 away from each other, the contact portions 2 of the pressure exerting members thus being moved from the dotted line positions to the full line positions of Figure 1 and shoving the members 9 and 10 before them along the supporting members 10 and 12 from the dotted line to the full line positions. The set screws 7 then may be tightened to hold the members 9 and 10 against 100 105 110

accidental relative movement on the supporting members 11 and 12 and toward each other. It will be manifest that sliding movement of the members 9 and 10 toward each other on the supporting members 11 and 12 may be effected by placing the forks of the contact members 2 in engagement with the remote walls of the members 9 and 10 and then manipulating the coupling nut 5 to draw the attaching ends 4 axially toward each other.

Obviously, my invention is susceptible of embodiment in forms other than that illustrated in the accompanying drawings and I 15 therefore consider as my own all such modifications and adaptations of the form of the device herein described as fairly fall within the scope of the appended claims.

I claim:—

20 1. A device of the character described comprising a pair of pressure exerting members, each being substantially L-shaped and consisting of a straight threaded attaching end portion, a straight contact end portion and a curved intermediate portion merging the straight attaching end portion and the contact end portion one into the other, a coupling nut connecting the attaching end portions of said members, whereby 25 the contact end portions of the members will be held substantially parallel with each other, each of said contact end portions being formed with a pair of forks at its extremity, said forks being offset laterally of opposite sides of the body of the contact end portion and the inner wall of each contact end portion being concavely curved at the junction of the forks of said contact end portion to closely fit over a pipe or like circular member which is straddled by the 30 forks.

opposite sides of the body of the contact end 35 portion and the inner wall of each contact end portion being concavely curved at the junction of the forks of said contact end portion to closely fit over a pipe or like circular member which is straddled by the 40 forks.

2. A device of the character described comprising a pair of pressure exerting members, each being substantially L-shaped and consisting of a straight threaded attaching 45 end portion, a straight contact end portion and a curved intermediate portion merging the straight attaching end portion and the contact end portion one into the other, a coupling nut connecting the attaching end 50 portions of said members, whereby the contact end portions of the members will be held substantially parallel with each other, each of said contact end portions being formed with a pair of forks at its extremity, 55 said forks being offset laterally of opposite sides of the body of the contact end portion and the inner wall of each contact end portion being concavely curved at the junction of the forks of said contact end portion to closely fit over a pipe or like circular member which is straddled by the forks, and a set screw threaded through a transverse opening in one of the forks of each contact 60 end portion for securing said contact end portion to the member which is straddled by said forks.

THOMAS PERRY BROCKETT.
